UNITED STATES PATENT OFFICE

151,204

DESIGN FOR A WATCH DIAL

George H. Adamson, Tecumseh, Mich.

Application December 9, 1947, Serial No. 143,079

Term of patent 14 years

(Cl. D42—10)

To all whom it may concern:

Be it known that I, George H. Adamson, a citizen of the United States, residing at Tecumseh, in the county of Lenawee and State of Michigan, have invented a new, original, and ornamental Design for a Watch Dial, of which the following is a specification, reference being had to the accompanying drawing, forming a part thereof.

The figure is a face view of a watch dial, showing my new design, the same being of conventional thickness.

I claim:

The ornamental design for a watch dial, substantially as shown and described.

GEORGE H. ADAMSON,
